[57] CLAIM

The ornamental design for a greens keeper, as shown and described.

DESCRIPTION

FIG. 1 is a perspective view of a greens keeper showing our new design;

FIG. 2 is a top view thereof;

FIG. 3 is a bottom view thereof;

FIG. 4 is a front view thereof;

FIG. 5 is a back view thereof;

FIG. 6 is a side view thereof;

FIG. 7 is a view of the opposite side thereof; and,

FIG. 8 is a front perspective view of a second embodiment thereof, the configuration of the rear of the brushes being identical to the front view.
